Primary Examiner — Lauren R Calve

(74) *Attorney, Agent, or Firm* — Cantor Colburn LLP

(57) **CLAIM**

The ornamental design for an oven knob, as shown and described.

DESCRIPTION

FIG. 1 is a front perspective view of an oven knob, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a cross sectional view taken along line 8-8 of FIG. 2.

The broken lines depict portions of the oven knob and environmental structure that form no part of the claimed design.

1 Claim, 8 Drawing Sheets
